COMBINED SILENT BUTLER AND CIGARETTE BOX

Martin Rosen, Flushing, N. Y.

Application March 4, 1953, Serial No. 23,878

Term of patent 3½ years

(Cl. D85—2)

To all whom it may concern:

Be it known that I, Martin Rosen, a citizen of the United States, residing at the city of New York, the county of Queens, State of New York, have invented a new, original, and ornamental Design for Combined Silent Butler and Cigarette Box, of which the following is a specification, reference being had to the accompanying drawing, forming a part hereof.

Fig. 1 is a side elevational view of a combined silent butler and cigarette box, showing my new design;

Fig. 2 is a partial cross-section of that shown in Fig. 1 in a side elevational view with the lid portions thereof open; and

Fig. 3 is a top plan view of that shown in Fig. 1.
I claim:

The ornamental design for a combined silent butler and cigarette box, as shown.
